UNITED STATES PATENT OFFICE

120,421

DESIGN FOR A JAR

Charles A. Howell, Winnetka, Ill., assignor to Pharma-Craft Corporation, Louisville, Ky.

Application February 5, 1940, Serial No. 90,053

Term of patent 14 years

To all whom it may concern:

Be it known that I, Charles A. Howell, a citizen of the United States, residing at Winnetka, in the county of Cook and State of Illinois, have invented a new, original, and ornamental Design for a Jar, of which the following is a specification, reference being had to the accompanying drawing, forming part thereof.

I claim:

The ornamental design for a jar, as shown.

CHARLES A. HOWELL.
